PAGE NOTCHING DEVICE

Frank W. Muth, Green Island, N. Y.

Application May 20, 1947, Serial No. 749,281

5 Claims. (Cl. 164—119)

1

In order to facilitate the turning of the pages in a book or the like, it is very convenient to have arcuate notches cut in the marginal edges thereof into which the thumb may be inserted to hold the pages underneath the notched page to prevent their turning when the notched page is turned. My invention, therefore, relates to a device of this character which may be used to cut an arcuate notch in the marginal edge of a book page or the like.

One of the objects of my invention is to provide a device of this character of extremely simple construction which can be made and sold very cheaply and yet will function efficiently for the intended purpose. Another object is to provide a device of this character in which the two principal elements can be readily molded from a hard plastic material and in which the few parts may be readily assembled in a novel manner.

I accomplish these objects by means of the novel elements and the combinations and arrangements thereof described below and illustrated in the accompanying drawing in which—

Fig. 1 is a top plan view of my device;

Fig. 2 is a section of Fig. 1 in the plane 2—2;

Fig. 3 is a left hand side elevation view of the device, as shown in Fig. 2, with the outer cylinder shown in section in a vertical plane through the axis thereof;

Fig. 4 is a fragmentary side elevation view of the device showing how the inner cylinder is temporarily flexed or deformed in order to insert it telescopically into the outer cylinder in assembling the device;

Fig. 5 is a fragmentary front elevation view of the device; and

Fig. 6 is a fragmentary plan view of a sheet of paper such as book page having a notch cut in the marginal edge thereof by my device.

Referring to the drawings—

My device comprises an outer tubular element 1, the inner surface of which is cylindrical and which is provided with a transversely-extending slot 2 therein in which the page or sheet to be notched is inserted. The inner bottom edge or line of intersection 8 of the bottom of the slot 2 with the inner surface of the tubular element 1 forms one cutting edge of a shear. In order to facilitate the insertion of the page in the slot 2, the entrance to the slot may be splayed, as shown at 3. The tubular element 1, above the center of the entrance to the slot 2 may be provided with an outwardly-extending projection 4, and the entrance to the slot along the lower edge thereof may have a circumferentially extending lip 5.

2

In the side of the tubular element 1 and diametrically opposite the center of the entrance to the slot 2, the element 1 is provided with a longitudinally-extending slot 6 which is closed at the top, as shown at 7, and which may, if desired, be closed also at the bottom.

Closely but slidably fitted within the outer tubular element 1 is an inner cylindrical, inverted, cup-like element 9 which is closed at the top by a head 10, a portion 11 of which projects outwardly beyond the periphery of the cylinder, as shown in Figs. 1, 2 and 4, to form a thumb grip. The skirt-like, depending portion of the element 9 is provided with a cutting edge 12, as shown in Figs. 2, 3 and 4, which is adapted to cooperate with the cutting edge 8 in the outer tubular element to form the shear. In order to make the shear easy to operate, the cutting edge 12 is preferably pointed at 13, where it first strikes the page or sheet to be notched, and is symmetrically inclined upwardly on each side of the point 13. The inner element 9, on the side opposite the point 13 of the edge 12, is provided with a projection 14 which is adapted slidably to interfit the slot 6 in the outer element 1. About midway between the point 13 of the cutting edge 12 and the projection 14, the inner element 9 is provided with substantially diametrically opposed, longitudinally-extending slots 15, open at the bottom, and against one side 16 of which the pin 17 is adapted to ride. The pin 17 extends substantially diametrically across the interior of the outer element 1 and is press-fitted, or otherwise secured, in the sides thereof.

In order normally to maintain the cutting edges 8 and 12 in spaced relation, as shown in Fig. 2, a light, helical spring 18, having an eye 19 in one end thereof through which the pin 17 passes, is compressed between the pin 17 and the inside of the head 10.

As pointed out above, both the inner and outer cylindrical members may be formed of a hard, plastic material or may be of metal, if desired. The slots 15 in the skirt of member 9, together with the resiliency of the material of which the member 9 is formed, make it possible temporarily to flex or deform the skirt of the member 9, as best shown in Fig. 4, so that it becomes possible to assemble the device first by positioning the pin 17 with the spring in engagement therewith and then pushing the inner cylindrical member 9 downwardly over the spring and into the outer cylindrical member in the manner shown in Fig. 4 until the projection 14 of the inner member snaps into the slot in the outer member. In order to

disassemble the parts, it is necessary to push the projection 14 inwardly by inserting a suitable tool through the slot 6 in contact with the projection 14 until the top of the projection 14 clears the closure 7 at the top of the slot 6, whereupon the cylindrical members may be pulled apart.

In use, the edge 26 of the sheet or page to be cut is inserted in the slot 2 and the member 9 is simply pushed telescopically downwardly into the outer element 1 against the compression spring 18, thus causing the cutting edge 12 to pass by the cutting edge 8 and to shear out of the page a notch, such as shown at 21 in Fig. 6.

While I have described my invention in its preferred embodiment, it is to be understood that the words which I have used are words of description rather than of limitation and that changes within the purview of the appended claims, may be made without departing from the true scope and spirit of my invention in its broader aspects.

What I claim is:

1. A device adapted for cutting a notch in the marginal edge of a book page to facilitate turning said page; said device comprising a cylindrical tubular element having a transversely-extending slot therein adapted to receive the edge of the page to be notched with one of the interior edges defining said slots forming one of the cutting edges of a shear, a second cylindrical element closely but slidably fitted in said tubular element and provided with a cutting edge adapted to cooperate with the cutting edge on said tubular element to form said shear; said tubular element being provided with a longitudinally-extending slot therein, closed at least at one end, and said second cylindrical element being provided with a projection thereon slidable in said slot to prevent relative rotation of said cylindrical elements; and a spring biased normally to hold said cutting edges in spaced relation to each other to allow the edge of said page to be inserted in said transversely-extending slot between said cutting edges.

2. The structure set forth in claim 1 in which the projection on said second cylindrical element is integral with said element.

3. A device adapted for cutting a notch in the marginal edge of a book page to facilitate turning said page; said device comprising an interior-

ly cylindrical element having a transversely-extending slot therein adapted to receive the edge of the page to be notched with one of the interior edges defining said slot forming one of the cutting edges of a shear, a second, exteriorly cylindrical element closely but slidably fitted in said first mentioned element and provided with a cutting edge adapted to cooperate with the cutting edge on said first mentioned element to form said shear; said interiorly cylindrical element having a longitudinally-extending slot therein closed at least at one end, and said second cylindrical element having a projection integral therewith and slidably in said slot to maintain said cylindrical elements in assembled relation; said second cylindrical element being formed of resilient material adapting it to be temporarily deformed, whereby said device may be assembled by telescopically pushing said second cylindrical element into said interiorly cylindrical element until said projection snaps into said longitudinally-extending slot in said interiorly cylindrical element; and a spring biased normally to hold said cutting edges in spaced relation to each other to allow the edges of said page to be inserted in said transversely-extending slot between said cutting edges.

4. The structure set forth in claim 1 in which the cylindrical elements are formed of a hard plastic material.

5. The structure set forth in claim 3 in which the cylindrical elements are formed of a hard plaster material.
